Nos. 1763

I. B. Jerome, of New Haven, Conn.
Letters Patent No 1763 dated Jan 16, 1863.

The schedule referred to in these Letters Patent and making part of the same.

To all whom it may concern:

Be it known that I, I. B. Jerome, of New Haven, in the County of New Haven, and State of Connecticut, have invented or produced a new and original Design for a Clock Case; and do hereby declare that the following is a full, clear, and exact description of the same, reference being had to the accompanying drawings, making a part of this specification in which,

Figure 1. is a front view of a clock case according to my design.

2

No. 1763

Figure 2, a section of the same taken in the line x. x. Figure 1.

Similar letters of reference indicate corresponding parts in the two Figures.

This design consists in a circular form of case having a dark or black colored front and periphery and uncompassed at its front edge with a gilded metal rim of concave form with a similar rim to form the frame of the glass plate which covers the dial.

In the accompanying drawings A, represents the body of the clock case the front and periphery of which are black or of a dark color, and B, represents a gilded rim of concave form such as is technically termed a "Scotia" as shown clearly in Figure 3. This rim B, is at the front edge of the case A, at its periphery C, is a rim of the same character or shape as the rim B, and which forms a frame for the glass plate which covers the dial of the clock. This rim C, is also gilded, and the two gilded rims form a pleasing contrast with the black or dark color of the case giving the latter a rich, chaste and finished appearance.

Having thus described my invention, what I claim as new and desire to secure by Letters Patent, is

The circular case A, of a black or other color, in connection with the gilded rims B, C, applied to the case as shown to form a new and original design for the article herein specified.
